MICROWAVE DEVICE

Rene A. Braden, Princeton, N. J., assignor to
 Radio Corporation of America, a corporation of
 Delaware

Application August 10, 1943, Serial No. 498,127

10. Claims. (Cl. 315—6)

1

This invention relates generally to microwave apparatus and more particularly to microwave modulation devices employing a plurality of cavity resonators coupled together to provide multi-resonant tuning characteristics.

In ultra-high frequency receiving systems it is often desirable to employ cavity resonators as tuning elements because of their inherently sharp resonant characteristics and high efficiency. However, in modulation circuits for combining input signals and oscillations from a local source of different frequency than the frequency of the input signals, the sharp resonant characteristics of cavity resonators have prevented efficient coupling of both signal and oscillator frequencies.

The instant invention contemplates a unique modulator device comprising a toroidal cavity resonator and means for generating an electron beam which is modulated by variations in electric field intensities established within the cavity resonator by input signals and local oscillations coupled thereto. Signals from an ultra-high frequency antenna are coupled to the cavity resonator by means of a coupling loop extending into the cavity resonator. Similarly, a source of local oscillations of a frequency different from the input signal frequency is coupled to the cavity resonator by means of a second coupling loop extending into said resonator. The electron beam is generated by a conventional thermionic cathode and passes through apertures in the constricted center portion of the cavity resonator to an anode electrode disposed adjacent one of said apertures. The cavity resonator is tuned to the mid-frequency between the signal frequency and the local oscillation frequency.

A second cavity resonator tuned to the same mid-frequency is coupled to the first cavity resonator by means of fixed or adjustable coupling means. The coupling should be fixed, or adjustable, to the value which causes the system as a whole to be resonant to both signal and oscillator frequencies. The two cavity resonators may be enclosed within a single evacuated envelope, or the second cavity resonator may be disposed outside of the evacuated envelope. Various modifications of the structure described heretofore are illustrated in the accompanying drawings and described in greater detail herein-after. Intermediate frequency signals may be derived from the anode electrode within the evacuated envelope and applied to a conventional intermediate frequency amplifier for subsequent final detection and amplification.

It should be understood that the various em- 55 Figure 1 is a schematic circuit diagram of one

2

bodiments and modifications of the invention disclosed herein have been limited to first detector circuits suitable for ultra-high frequency receivers merely for the purpose of simplifying the explanation thereof. Broadly, the invention may be applied to various other radio tuning and modulation circuit elements where multi-frequency or band-pass characteristics are desired.

Among the objects of the invention are to provide an improved method of and means for applying signals of a plurality of frequencies to a cavity resonator. Another object of the invention is to provide an improved method of and means for applying signals of both input signal frequencies and local oscillation frequencies to a cavity resonator type ultra-high-frequency detector. Another object of the invention is to provide an improved cavity resonator type ultra-high-frequency modulation device comprising an evacuated envelope enclosing a cavity resonator tuned to an operating frequency wherein an electric field is established for modulating electrons passing through a constricted portion of said cavity resonator, and means for coupling to said cavity resonator a second cavity resonator tuned to the same operating frequency in a manner providing resonance at two operating frequencies. Another object of the invention is to provide an improved ultra-high-frequency modulation device including two cavity resonators tuned to the same or different operating frequencies and coupled together to provide a multi-resonant device, and means for modulating an electron beam by directing said beam through one of said cavity resonators.

A further object of the invention is to provide an improved ultra-high-frequency first detector circuit for an ultra-high-frequency superheterodyne receiver wherein band-pass tuning characteristics are provided by a plurality of cavity resonators coupled to a cavity resonator enclosed within an evacuated envelope, wherein an electric field may be established within the enclosed cavity resonator to modulate an electron beam in accordance with input signal frequency signals and frequencies from a source of local oscillations. An additional object of the invention is to provide means for coupling a plurality of cavity resonators tuned to the same or different operating frequencies to provide multi-frequency or band-pass characteristics in at least one of said cavity resonators.

The invention will be further described by reference to the accompanying drawings of which

embodiment thereof; Figure 2 is a schematic circuit diagram of a second embodiment thereof; Figure 3 is a schematic circuit diagram of a modification of the embodiment disclosed in Figure 2; Figure 4 is a schematic circuit diagram of a third embodiment of the invention and Figure 5 is a schematic circuit diagram of a modification of the embodiment of the invention disclosed in Figure 4. Similar reference characters are applied to similar elements throughout the drawing.

Referring to Figure 1, an evacuated envelope 1 encloses a cathode 2, heated by a heater element 3, and an anode electrode 4. Connections are brought out through the evacuated envelope for the cathode heater and anode electrodes. A conventional toroidal cavity resonator, having apertures 5 at its center constricted portion, is disposed between the cathode 2 and anode 4 in such a manner that the electron beam between the cathode and anode electrodes passes through the apertures 5 of the cavity resonator 6. A first coupling loop 7 extending into the cavity resonator 6, is connected to a receiving antenna 8. A second coupling loop 9, also extending into the cavity resonator 6, is connected to a source of local oscillations 10. A third coupling loop 11, extending into the cavity resonator 6, is coupled to a second cavity resonator 12 which is disposed outside of the evacuated envelope 1. The coupling to the second cavity resonator 12 is provided by a coupling loop 13 extending therein. The coupling loops 11 and 13 within the first and second cavity resonators 6, 12, respectively, are coupled together by an adjustable coupling device 14 illustrated herein as a pair of parallel disposed coupling loops 15, 16. It should be understood that any other adjustable means of coupling the loops 11, 13 in the two cavity resonators may be employed to equal advantage. The second cavity resonator 12 is tuned to resonate at the frequency of the source of local oscillations 10. If desired, both cavity resonators may be tuned to the mid-frequency between the signal and oscillator frequencies.

The effect of coupling the two cavity resonators 6, 12, by means of the coupling circuit described, is to provide a device which responds efficiently at both signal input and local oscillation frequencies. The effect is quite similar to providing relatively large mutual coupling between conventional resonant circuits tuned to the same or slightly different operating frequencies. Since the first cavity resonator 6 is thereby caused to have two degrees of freedom, an electric field will be established therein at both the signal input and local oscillation frequencies, and will modulate the electron beam accordingly. Therefore, a modulation frequency equivalent to the sum or difference between the signal input and the local oscillation frequencies may be derived from the anode electrode 4 and applied, through an inductively coupled output circuit, to the input of a conventional intermediate frequency amplifier, not shown.

Figure 2 discloses a second embodiment of the invention which is similar to that described in Figure 1, but wherein the two toroidal cavity resonators, 6, 12 respectively, disposed in parallel planes, are enclosed within a common evacuated envelope 1. The cavity resonators may be tuned halfway between the signal input and the local oscillation frequencies. The two resonators intersect at the points 17 and include a common aperture 18 to provide a desired degree of cou-

pling therebetween. The size of the common aperture 18 between the cavity resonators 6, 12 will determine the coupling between the two resonators and thus the band-pass characteristics of the device. The first cavity resonator includes apertures 5 at its constricted center portion which permit an electron beam to pass from the cathode 2 to the anode 4 in the same manner as described heretofore in Figure 1. The operation of the devices of Figure 1 and Figure 2 are identical except that in the latter device fixed coupling is provided between the two cavity resonators. The center portion of the device of Fig. 2 may be supported by radial arms extending therefrom across the aperture 18 to the junction 17 of the outer resonator shells 6, 12.

Figure 3 is a modification of the embodiment disclosed in Figure 2 wherein the toroidal cavity resonators intersect only at the point 19 of the outer peripheral portions of the first and second cavity resonators 6, 12 respectively. The two cavity resonators 6, 12, respectively, are tuned to the signal input and local oscillation frequencies, or to the mean of said signal and oscillator frequencies, and the structure of the device is identical in all other respects to that of the device described in Figure 2.

It should be understood, however, that the coupling loops 7 and 9 from the signal input circuit 8 and the source of local oscillations 10, respectively, may be coupled to either the second cavity resonator 12, or to the first cavity resonator 6 as indicated by the switches S1, S2. The essential difference between the modifications disclosed in Figures 2 and 3 is in the overall shapes thereof, since the operating electrical characteristics of both devices are substantially identical and coupling is obtained between the two resonant cavities 6, 12 respectively, by means of the common aperture 18 therebetween in the same manner as described in Figure 2.

Figure 4 is similar to the device described in Figure 1 with the exception that separate tuning means have been provided for the signal input and local oscillation coupling circuits. The evacuated envelope 1 includes a cathode 2, heater element 3 and anode electrode 4, and a first toroidal cavity resonator 6 having apertures at the constricted center portion wherein the apertures 5 are in the path of the electrons from the cathode to the anode electrode 4.

The source of local oscillations 10 is connected through a coupling loop 20 to a second cavity resonator 22, which may be tuned by means of a tuning screw 23 extending therein. The second cavity resonator 22 includes an output coupling loop 24 which is connected through a conventional trombone line adjusting unit 25 and concentric transmission line 26 to an oscillator frequency coupling loop 9 extending into the first toroidal cavity resonator 6. The first and second cavity resonators 6, 22 are tuned to a frequency midway between the signal and local oscillator frequencies, and are so coupled that there are two resonant frequencies corresponding to the signal and oscillator frequencies.

Signals derived from the antenna 8 are coupled to a third cavity resonator 27 by means of an input coupling loop 28. The resonant frequency of the third cavity resonator 27 is adjusted to the signal frequency, and may be varied by means of an adjusting screw 29 which varies the spacing between the constricted center side walls of the toroidal cavity, thus resulting in broadened resonance at the signal frequency.

An output coupling loop 30, extending into the third cavity resonator 27, is coupled, through a second trombone line adjusting unit 31, to the signal input coupling loop 7 in the first cavity resonator 6, enclosed within the evacuated envelope 1.

Figure 5 shows a typical modification of the signal input circuit of Figure 4, wherein a balanced input loop 35 is connected to the signal input loop 7 of the first cavity resonator 6 which is enclosed within the evacuated envelope 1. The characteristics of the apparatus within the evacuated envelope 1 are identical to that described in Figure 4. The antenna 8 is connected to predetermined points on the balanced loop 35 to provide effective coupling thereto. The balanced loop circuit 35 is tuned by means of a tuning stub 36 connected thereto at a second predetermined point. The tuning stub 36 is tuned by means of a shorting bar 37.

A second coupling loop 9, extending into the resonant cavity 6 within the evacuated envelope 1, may be coupled to the source of local oscillations 10 in the same manner as described and illustrated in Figure 4.

Thus the invention described comprises several embodiments and modifications of a unique ultra-high-frequency modulation device employing a plurality of cavity resonators to provide multi-frequency or band-pass frequency response.

I claim as my invention:

1. Multi-resonant microwave apparatus including two resonant devices each tuned to predetermined resonant frequencies, said resonant devices being mutually coupled together, means coupled to only one of said devices for establishing therein standing waves at two different frequencies, a predetermined one of said devices being adapted to have an electric field established in a predetermined direction therein, and means coupled to only said predetermined one of said devices defining an electron beam path extending through only said predetermined device in a direction parallel to the path of said electric field whereby said electron beam is modulated by both of said waves.

2. Apparatus as claimed in claim 1 including means coupled to one of said devices for deriving signals from said one of said devices in response to said modulated electron beam.

3. Multi-resonant microwave apparatus including two intersecting cavity resonators mutually coupled together and tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators defining an electron beam path extending through only said predetermined resonator in a direction parallel to the path of said electric field to modulate said beam at both of said frequencies.

4. Multi-resonant microwave apparatus including two cavity resonators mutually coupled together and differently tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators

defining an electron beam path extending through only said predetermined resonator in a direction parallel to the path of said electric field to modulate said beam at both of said frequencies.

5. Multi-resonant microwave apparatus including two coaxial intersecting cavity resonators mutually coupled together and tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators defining an electron beam path extending through only said predetermined resonator in a direction parallel to the path of said electric field to modulate said beam at both of said frequencies.
6. Multi-resonant microwave apparatus including two coaxial toroidal cavity resonators mutually coupled together and tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators defining an electron beam path extending through only said predetermined resonator in a direction parallel to the path of said electric field to modulate said beam at both of said frequencies.
7. Multi-resonant microwave apparatus including two cavity resonators having adjacent similar portions mutually coupled together and tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators defining an electron beam path extending through only said predetermined resonator in a direction parallel to the path of said electric field to modulate said beam at both of said frequencies.
8. Multi-resonant microwave apparatus including two cavity resonators having adjacent peripheral portions mutually coupled together and tuned to be mutually resonant at two different frequencies, means coupled to said resonators for establishing therein standing waves at each of said frequencies, a predetermined one of said devices being adapted to have an electric field established in a predetermined direction therein, and means coupled to only said predetermined one of said resonators defining an electron beam path extending through only said predetermined resonator in a direction parallel to the path of said electric field to modulate said beam at both of said frequencies.
9. Multi-resonant microwave apparatus including two resonant devices each tuned to the same resonant frequencies, said resonant devices being mutually coupled together, means coupled to one of said devices for establishing therein standing waves at two different frequencies, a predetermined one of said devices being adapted to have an electric field established in a predetermined direction therein, and means coupled to only said predetermined one of said devices defining an electron beam path extend-

ing through only said predetermined device in a direction parallel to the path of said electric field whereby said electron beam is modulated by both of said waves.

10. Multi-resonant microwave apparatus including two resonant devices each tuned to predetermined resonant frequencies, said resonant devices being mutually coupled together, tunable means coupled to one of said devices for establishing therein standing waves at two different frequencies, a predetermined one of said devices being adapted to have an electric field established in a predetermined direction therein, and means coupled to only said predetermined one of said devices defining an electron beam path extending through only said predetermined device in a direction parallel to the path of said electric field whereby said electron beam is modulated by both of said waves.
